JOHANN EICHMÜLLER, OF NUERMBERG, GERMANY, ASSIGNOR TO THE
FIRM OF EUGENE DIETZGEN CO., OF NEW YORK, N. Y.

ADJUSTING MECHANISM FOR SCREW-THREADED NEEDLE-POINT INSERTIONS OF COMPASSES.

No. 808,644.

Specification of Letters Patent.

Patented Jan. 2, 1906.

Application filed April 11, 1905. Serial No. 255,027.

To all whom it may concern:

Be it known that I, JOHANN EICHMÜLLER, manufacturer, a subject of the German Emperor, residing at Nuremberg, Bavaria, Germany, have invented new and useful Improvements in Adjusting Mechanisms for Screw-Threaded Needle-Point Insertions of Compasses, of which the following is a specification.

10 This invention has for its object a fine-adjusting mechanism for screw-threaded needle-point insertions for compasses in which the nut mounted on the needle is made disk-shaped and secured against axial displacement by being inserted in a recess corresponding in width to the thickness of the disk in the foot of the needle-point, arranged at right angles to the needle-foot of the leg of the compasses.

20 This improved fine-adjusting mechanism is shown in one form of construction in the accompanying drawings.

Figure 1 is an elevation; Fig. 2, an elevation turned at right angles to the previous view, and Fig. 3 a vertical section further again turned at right angles to Fig. 2.

The needle-foot *a* of the leg *b* of the compasses is provided with a smooth perforation *d*, adapted to receive the needle *c*, which perforation is continued on the inside of the compass-leg *b* as a semicylindrical groove *e*. A milled disk *f* is mounted in a recess *g*, formed at right angles to the axis of the needle, the width of which recess corresponds to the thickness of the disk *f*, so that the latter cannot be axially displaced. On one side of the needle-foot *a* a stirrup-shaped enlargement *h*, surrounding the recess *g*, is provided, in the yoke of which enlargement a pressure-screw *i*, adapted to be adjusted against the edge of the disk-shaped nut *f* is mounted. The insertion-needle *c* is also provided with a longitudinal groove *k*, in which a small screw *l*, arranged on the needle-foot *a*, engages, and thereby prevents the needle revolving.

If the pressure-disk *i* be released, the needle which is prevented rotating is axially displaced in one direction or the other by the disk

f being turned in one or other direction. In order to fix the needle in the desired position, 50 it is only necessary to press the pressure-screw *i* against the edge of the disk *f*, which is thereby secured against rotation and in this manner prevents any unintentional displacement of the needle. 55

I declare that what I claim is—

1. In combination in a compass having a needle-foot having a longitudinal bore therein, a screw-threaded needle adapted to fit in said bore, said foot having a lateral recess 60 therein, a disk fitting in said recess and having a screw-threaded central opening through which the needle passes, and means for preventing the needle from rotating when the disk is turned, substantially as described. 65

2. In combination in a compass having a needle-foot provided with a smooth longitudinal bore, a screw-threaded needle fitting in said bore, said needle having a longitudinal recess therein, a screw in said foot having its 70 end engaging in said recess so as to prevent the needle from turning, said foot having a lateral recess and a disk fitting in said recess and having a central screw-threaded hole through which the needle passes. 75

3. In combination in a compass having a needle-foot provided with a smooth longitudinal bore, a screw-threaded needle fitting in said bore, means for preventing the needle from rotating, said foot having a lateral recess, a disk fitting in said recess and having a 80 central screw-threaded hole through which said needle passes, a stirrup-shaped enlargement connected to the needle-foot and inclosing on one side the said recess and a pressure-screw mounted in said enlargement and having its end adapted to engage with the disk so as to prevent movement of the same. 85

In testimony whereof I have signed my name to this specification in the presence of 90 two subscribing witnesses.

JOHANN EICHMÜLLER.
